UNITED STATES PATENT OFFICE

JOHN R. MITCHELL, OF TRENTON, NEW JERSEY

GUIDE FOR TEXTILE MACHINES

Application filed September 20, 1928. Serial No. 307,218.

This invention relates to thread guides and is particularly adapted for use in machines for winding and spooling of silk thread or yarn. Thread guides of this type are usually formed of porcelain or other vitreous material and are provided with a slot to receive and guide the thread.

An object of the present invention is to so construct the guide as to greatly lessen the objectionable wear due to the friction of the thread, thereby prolonging the life of the guide and increasing its efficiency in delivering the thread uniformly.

The present invention is an improvement 15 on the guide disclosed in my prior Patent 1,448,076, March 13, 1923, and embodies the essential features of that construction as well as further improvements tending to increase the efficiency of the guide and to prolong the 20 length of life thereof.

A further object of this invention is to provide for the renewing of that surface of the guide which receives the most wear resulting from the friction of the moving thread. It 25 has been found in practice that the surface of the guide on which the thread rests during its passage through the guide is subjected to considerable wear necessitating frequent replacement of the entire guide.

30 While the construction disclosed in my prior patent has been found particularly effective in preventing localized wear on the guide, the present arrangement is intended to provide for the removal and replacement of that portion of the guide which receives the most wear, thus obviating the necessity for replacing the entire guide when only a portion thereof has become worn and unfit for 35 service. It is therefore a feature of this invention to provide a removable wear piece which can be easily inserted in the guide and which can be readily replaced when worn.

A further object of the invention is to provide a removable wear piece having a plurality of surfaces on which the thread may bear so that when one engaging surface of the piece is worn, the piece may be removed and reinserted so as to present another surface for engagement with the thread, thereby

prolonging the life not only of the guide but of the wear piece itself.

A further object of the invention is to so construct the guide and wear piece that the thread will be prevented from engaging with the bottom of the guide slot, thus eliminating 55 wear on that portion of the slot, and in so disposing the wear piece within the guide that the thread will be permitted to move up and down in a narrow thread discharge slot, thus 60 distributing the wear along the walls of this slot.

Another feature of this invention is the provision of a relatively wide opening in the guide through which the thread may enter 65 so that varying portions of the thread supporting surface of the wear piece may be engaged by the thread as the angle of entrance of the thread is varied, in order to distribute the wear along the entire supporting surface. 70

A further object of the invention is to provide a recess in the upper surface of the guide into which the wear piece may be dropped, the latter being retained in the recess by gravity, thus avoiding the use of a retaining 75 device for holding the wear piece in place and facilitating the removal, reversal, and replacement of the piece.

Various other objects and features of the invention will be apparent from the following description and claims taken in connection with the accompanying drawings, in which:

Figure 1 is a perspective view of the improved guide showing the removable wear 80 piece in position therein;

Figure 2 is a front elevation of the guide;

Figure 3 is a view in plan of Fig. 2;

Figure 4 is a section on the line 4—4 of Fig. 2;

Figure 5 is a section on the line 5—5 of Fig. 4; and

Figure 6 is a perspective view of the removable wear piece.

In the embodiment of the invention shown 85 herein for the purpose of illustration, there is disclosed a guide block 10 which is preferably formed with the main portion of its sides inclined symmetrically toward each other from the bottom to the top and its upper sur- 100

face slightly inclined downwardly from the ends to the central transverse guide slot which is indicated generally at 11. The bottom of the block 10 is formed with a longitudinal depression 12, V-shaped in section, so as to adapt it to fit the upper V-shaped surface of the usual thread guide carrying rail, illustration of which is deemed unnecessary. The end portions of the top guide have small longitudinal depressions 14 and 15, V-shaped in section, and adapted to receive well-known means, not shown, for securing it to the carrying rail.

It will be understood that the foregoing details of description do not constitute part of the present invention and may be modified in any desired manner to adapt the guide for use in various types of machines.

The guide slot 11 is, according to the present invention, preferably constructed in two portions, a wide entrance portion 17 for receiving the entering thread and a narrow discharge portion 18. In the modification illustrated, I have shown these portions of the guide slot as tapered from the front to the rear of the guide, so that the thread encounters the narrowest portion of the guide slot as it leaves the guide.

The lower surfaces of the entry and discharge portions of the guide are preferably rounded, as shown in Figure 4, for convenience in manufacture and to eliminate any possible friction on the thread.

Intermediate the entry and discharge portions of the guide slot, the guide is provided with a recess 20 which communicates with the slot portions 17 and 18 and preferably extends transversely of the direction of thread feed. Viewing the construction in a different light, the transverse guide slot 11 may be considered as being intersected by a longitudinally extending recess 20. Whereas this recess is preferably formed with substantially rectangularly disposed flat walls as disclosed herein, it may obviously be variously shaped and dimensioned. A removable wear piece 22, which is separately shown in Figure 6 of the drawing, is adapted to be dropped in recess 20, and for that purpose is preferably constructed of such a shape and with such dimensions that it will closely fit within the walls of the recess without binding, the upper face of the wear piece, when in position in the guide, being preferably convexly curved to eliminate unnecessary friction and to insure smooth passage of the thread through the guide. According to my invention, both the upper and lower surfaces 23 and 24 of the wear piece are rounded in this manner so that when one surface is so worn as to reduce its efficiency or render it useless, the wear piece may be removed, reversed, and reinserted to present a fresh surface on which the thread may bear.

It will be understood that the depth of the

recess 11 and the corresponding dimension of the wear piece are so proportioned that the thread is not permitted to bear on the bottom of the guide slot, but passes over and rests on the wear piece only, thus eliminating any wear on the guide other than at the sides of the guide slot.

It will further be seen that this engaging surface is so located with respect to the discharge portion 18 of the slot that the thread is permitted to move up and down therein, as in the construction disclosed in my prior patent above mentioned. In this way the wear due to friction on the walls of the discharge portion of the guide slot is distributed and the life of the guide correspondingly prolonged. It will further be seen that by reason of the provision of the wide entry portion 17 of the guide slot and the continually changing angular direction of entry of the thread into the guide, the thread will be permitted to shift longitudinally of the wear piece and will distribute the wear along this member.

The guide block and wear piece may be constructed of any suitable material, but are preferably formed of vitreous material such as porcelain.

Although a specific embodiment of the invention is shown for purposes of illustration, it will be understood that it is not limited to that specific form beyond the extent indicated in the following claims.

Having thus described the invention, what is claimed as new and desired to be secured by Letters Patent is:

1. As an article of manufacture, a thread guide comprising a one-piece block having a transverse guide slot, and provided with a recess intersecting said guide slot and extending downwardly from the upper surface of the block, whereby a movable wear piece may be inserted downwardly in said recess and held therein by gravity.

2. A thread guide comprising a guide block having a wide entry guide slot, a narrow discharge guide slot, and a centrally disposed recess extending downwardly from the upper surface of said block and communicating with both of said slots, and a removable wear piece seated in said recess having an upper surface on which the thread may bear, said surface being disposed above the bottom of said guide slots.

3. As an article of manufacture, a removable wear piece for thread guides consisting of a substantially rectangular parallelepipedal element having two opposite sides thereof slightly convexed to present smooth unbroken surfaces on which the thread may bear, whereby the element may be reversed in position to prolong the life thereof.

4. A thread guide consisting of a guide block having a substantially straight walled recess disposed centrally thereof, a portion

of the front wall of said recess being cut away to constitute an entrance guide for the thread, and the rear wall thereof being provided with a narrow slot forming a discharge 5 guide, and a substantially rectangular parallelepipedal element seated in said recess and having a slightly convexed upper surface on which the thread may bear, said element being so positioned as to maintain the thread 10 out of contact with the bottom of said guides.

5. A thread guide consisting of a guide block having a centrally disposed recess in the top face thereof, a portion of the front wall of said recess being cut away to form a 15 wide entrance guide for the thread, and the rear wall thereof being vertically slotted to form a narrow discharge guide tapering toward the front of the block, and a removable wear piece seated in said recess, said wear 20 piece being provided with a curved upper surface on which the thread may bear for maintaining the thread out of contact with the bottom of the guides and permitting the thread to move up and down in the discharge 25 guide to distribute the wear due to friction.

6. A thread guide consisting of a guide block having a centrally disposed recess in the top face thereof and being provided with a wide entrance guide slot and a narrow discharge guide slot for the thread, said slots 30 communicating with said recess, and a wear piece adapted to be dropped in said recess and having convexly curved faces on two opposite sides thereof on which the thread may 35 bear, whereby the wear piece may be easily removed and replaced or reinserted in reversed position.

7. A thread guide consisting of a guide block having a transverse guide slot, and 40 provided with a recess intersecting said slot, and a removable wear piece for insertion in said recess, said wear piece having two sides rounded off to present a smooth surface on which the thread may bear, whereby the piece 45 may be inserted with either rounded side thereof disposed in position for engagement with the thread.

8. A thread guide consisting of a guide block having a transverse guide slot and provided with a flat sided recess intersecting said slot, and a removable wear piece adapted for 50 insertion in said recess having flat sides for cooperation with said recess and two oppositely disposed curved sides on which the 55 thread may bear, whereby said piece may be reversed in position to present either of said curved sides upwardly to support the thread above the bottom of said guide slot.

9. A device as specified in claim 1 in combination with a wear piece arranged in said recess.

10. A device as specified in claim 1 in combination with a wear piece arranged in 60 said recess, said wear piece having a curved 65

upper surface above the bottom of said guide slot.

In testimony whereof I hereunto affix my signature.

JOHN R. MITCHELL.
